UNITED STATES PATENT OFFICE.

GUSTAV HÜBNER, OF PLAUE, GERMANY.

TAMBOUR-FRAME-MOVING MECHANISM FOR EMBROIDERING MACHINES.

1,154,397.

Specification of Letters Patent. Patented Sept. 21, 1915.

Application filed March 26, 1912. Serial No. 686,266.

To all whom it may concern:

Be it known that I, GUSTAV HÜBNER, a subject of the King of Saxony, residing at Plauen, Vogtland, Saxony, Germany, have 5 invented certain new and useful Improvements in Tambour-Frame-Moving Mechanism for Embroidering Machines, of which the following is a specification, reference being had therein to the accompanying drawing.

The present invention relates to means for automatically adjusting the tambour frames for embroidering machines, in which needle bearing levers adjusted from the 15 jacquard card and lifted by grades, act on levers which can be oscillated to and fro, and adjusted in height for the indirect displacement of the embroidering frame.

In order to prevent inaccuracies in the 20 lifting action of the needle bearing levers, to cause displacement of the tambour frames, these were formerly secured by intricate mechanism which can now be dispensed with, because the present invention 25 provides double armed bearing levers having the same center of motion, mounted on a frame-like standard, which is intermittently caused to swing, and when they are lifted, are retained in their adjusted position by a shiftable bar. In addition, further means have been provided to produce 30 different speeds of the jacquard in one pattern by the insertion of a rapid or slow speed gear in the driving mechanism when 35 using the jacquard card.

In the accompanying drawings, in which the same letters refer to the same parts throughout the several views, one form of embodiment of the invention is presented 40 herein.

In the drawings Figure 1 is a vertical section of the machine. Fig. 1^a is an enlarged view of the levers on the shaft 14. Fig. 2 is a view similar to Fig. 1, showing the parts 45 in a different relation. Fig. 3 is illustrative of the driving mechanism in plan view. Fig. 4 shows the frame-like standard in a special position for the needle carrying le-

vers and Figs. 5, 6 and 7, show details of the device.

The shaft 2 gets its propulsion from the shaft 1, provided with a pulley by means of chain wheels 3 and 4, or 5 and 6, and the chains belonging thereto. Keys 55 are for connecting the gears 3 and 5, to the shaft 55 1, which gears are adapted to be disconnected from the keys 55.

The shaft 2 has a cam 7, fitted thereon for moving the frame 9 which supports the needle levers 10, and, in addition, has a cam 60 8, for operating lever 24 which engages hook 22 on bar 11, and, at the end, a disk 12, imparting intermittently, partial rotations to the oscillating levers 17, by means of a rod 13, such levers being operated upon, in the upper part of the machine, by the shaft 14, adjustable in height and supported on bent extensions 16 of the intermediate levers 15. The hook levers 30, which are operated by pushers 29, push up the fingers 65 15^a which lift the member 15.

On the shaft 18, of the frame 9, needle levers 10 are loosely oscillatable, and when in operative position, as shown in Fig. 4, they rest on the front ledge of the frame 9, 75 so that their extremities, provided with knobs 19, may engage the recess 20, of the bar 11, the latter having a lateral guide member 21, guided by a roll 27, and adjustable on the frame 9. The guide member 21 80 has a lateral hook 22, engaging a slot 23, of a tappet lever 24, the arm 25, whereof is kept adjacent to the disk 8 by a spring 26, actuating the guide members 21, in one direction. The frame 9, has pivotally secured 85 thereto, a slide bar, the roll 28, of which engages the groove 12, of the cam 7. The armed, intermediate levers 15, have their support on the cross-ledge 31. The purpose of pivotally mounting the fingers 15^a on 90 the levers 15, is to permit the swinging of fingers 15^a on levers 15, while the fingers are operating the levers.

Each separate adjusting member 32, is guided by four rollers 33, and supplied, intermediate its ends with two adjacent pin

heads 34, and two adjacent pin heads 34^a shown in detail in Figs. 5 and 6, and which are tapered in opposite directions and are pressed away from the adjusting arm by 5 means of springs. With these pin heads the before mentioned oscillating members 17, coöperate.

Each lever 17 is provided on its upper and lower ends and on the side facing the 10 pin heads with pairs of notches 17^a, 17^b, the notches of each pair slanting in opposite directions and with which notches 17^a, 17^b, the pin heads 34, 34^a coöperate. This construction permits the lever 17, according to 15 its vertical position, to reciprocate the member 22.

On the axle 35, of the upper part of the frame, levers 36 are mounted, corresponding in number to the number of the adjusting 20 members 32. These are engaged on the one hand by means of slotted ends, with the bolts 37 of the adjusting members 32, and are connected on the other hand with an adjusting mechanism for the tambour 25 frame of the embroidering machine, fitted in the known manner with slide plates 39, and sliding pieces 40.

The device for rapid and slow speed gear, 30 comprises a rod 44, fitted with two rock arms 41 and 42, and rotatable in bearing 43 and 43^a said rod 44 being articulately connected with one of the adjusting arms by means of rock arm 41, while rock arm 42 joins said rod at its lower end with a slide 35 bar 45. By means of slotted projections 46 and 47, as shown in Fig. 3, the slide has a displacing action on the chain wheel 3 or 5, according to the direction of oscillation of rod 44.

40 According to Fig. 3, the drive for slow speed gear (5, 6,) is thrown in and the chain wheel 3, is thrown out of gear.

The operation of the device is as follows:—The adjustment of the needle levers 10, effected by the oscillation of the frame 9, is retained by the movement of the recessed bar 11, in the direction of the arrow 1, as in Figs. 4 and 1, by causing the lowered needle levers to enter the recess 20 of the part 11, and the raised needle lever 10 to abut the chamfering 48, where they are secured with their knob 19, by a rib 49, of the bar 11, as in Fig. 1. When now the cam 7 imparts an oscillation to the frame 9, the pushers 29, of the lifted needle levers 10, raise up the intermediate levers 15, and therewith also the oscillating levers 17 which immediately afterward are turned by the pitman 18, into the position as shown 50 in Fig. 2: on moving however back into their initial position, they draw back again the adjusting arms 32 which might have been displaced. A needle lever 10, which is not lifted but has fallen into an opening, 55 of the pattern card 50 has no raising effect

on an intermediate lever 15, or on the oscillating lever 17, so that during the common rotation, the latter is operating with its full face against a key-head 34^a as in Figs. 2, 5 and 6, thereby shifting the adjusting arm 32, belonging thereto, in the direction of the arrow 2, (see Fig. 2.) This displaces, by means of the lever 36^a and of the rod 38^a, a slide plate 39. When the needle levers 10, or the frame 9, are moving back, owing to the raising of the roll 28, of the cam 7, the levers 10 are released from the bar 11, by operation of cam 8 on lever 24, which engages hook 22, on bar 11, and, owing to the needle levers own weight they fall back again into their initial position, as in Fig. 4.

Immediately afterward the cam 7 operates by means of the frame 9 the needles of the levers 10 onto the pattern card so that the needle levers 10, may be adjusted anew and secured by the bar 11, in their action, whereby they are made to operate on the intermediate levers 15 and the adjusting members 32.

What I claim and desire to secure, is:— 90

1. In a device of the character described, a frame, needle levers mounted on said frame, means to intermittently vibrate said levers, a transverse bar having a recess, said levers adapted to engage said recess and be retained in the adjustment effected by the pattern card, adjusting arms adapted to operate the embroidery frame and one armed levers adapted to communicate movement from said needle levers to said adjusting arms. 95

2. In a device of the character described, a frame, a driving shaft journaled on said frame, a driven shaft, speed controlling means connected with said driving shaft and said driven shaft, a vertical bar, a cam on said driven shaft longitudinally reciprocating said vertical bar, a rocking needle lever actuated by said vertical bar, guide rollers, a horizontally movable frame mounted on said guide rollers, means by which said rocking needle lever controls the reciprocations of said movable frame, including a vertically adjustable and oscillatory bar connected to said movable frame and means 110 connecting said movable frame with the tambour frame. 115

3. In a device of the character described, a driving shaft a driven shaft, adjustable sprocket wheels on one of said shafts, means to connect and disconnect said adjustable wheels with said shaft, cams on said driven shaft a rod suitably journaled at its lower end and having a slet in its upper end and an inclined rigid projection spring-held against one of said cams, a recessed transverse bar, lifting needle levers, pushers on said needle levers, hook-levers actuated by said pushers, horizontal levers 15, rock arms 15^a, pivoted on said horizontal levers and 125

engaged by said hook levers, an oscillating bar 17 said levers 15 operating to control the vertical position of the oscillating bar 17, a rod actuating the tambour frame and means operatively connecting said oscillating bar with said rod for actuating the tambour frame, as herein set forth.

In testimony whereof I affix my signature in the presence of two witnesses.

GUSTAV HÜBNER.
